UNITED STATES PATENT OFFICE

2,416,269

WINDOW SASH

Hubert W. Paul, Toledo, Ohio, assignor to Owens-
Illinois Glass Company, a corporation of Ohio

Application February 1, 1943, Serial No. 474,279

8 Claims. (Cl. 189—76)

1

My invention relates to improvements in window sash. An object of the invention is to provide a structure in which loss of heat is reduced to a minimum. Window frames or sash made of metal as generally constructed, permit an escape of large amounts of heat conducted therethrough. Owing to such heat conductivity, double glazing for use with metal sash has been rendered comparatively inefficient as a means of preventing heat losses.

An object of the present invention is to reduce such heat losses to a minimum by the provision of a window sash particularly adapted for use with hollow window panes or blocks, as well as for either single or double glazing, so constructed as to permit the transmission and escape of comparatively little heat.

A further object of the invention is to provide a construction suitable for use in rooms where exposed metal frames would be subjected to the destructive action of corrosive fumes or gases. To this end the invention provides a metal framework or sash of such construction that no portion of the framework between the adjoining panes of glass projects into an exposed position, and in which the framework is adequately protected by sealing material which is inert or resistant to the action of such destructive gases.

A further object of the invention is to provide a window comprising a metal sash or framework, with insulating material overlying and covering the spacing bars between the edges of adjoining window panes.

Other objects of the invention will appear hereinafter.

Referring to the accompanying drawings:

Fig. 1 is a fragmentary, sectional view in perspective illustrating a sash embodying one form of my invention.

Fig. 2 is a fragmentary part sectional elevation of the same.

Fig. 3 is a fragmentary perspective view of the sash on a smaller scale.

Fig. 4 is a fragmentary elevation of a sash with a modified form of means for attaching the glass thereto.

Fig. 5 is a view on a larger scale, of a portion of the frame as viewed from the opposite side from that of Fig. 4, and also showing the corners of several panes of glass mounted therein.

Fig. 6 is a sectional elevation showing particularly one of the attaching devices.

Fig. 7 is an elevation showing a further modification of the frame and the holding devices for securing the glass to the frame.

2

Fig. 8 is a sectional elevation, with parts broken away, of the structure shown in Fig. 7.

Referring to Figs. 1, 2, and 3, the sash as illustrated, comprises a rectangular frame 10, which may be made of steel or other metal, and inner cross bars 11 integral therewith, thereby forming a panel framework. Each of the sides and ends of the frame 10 is in the form of a longitudinal bar 12 or body portion having a vertical front face, and an integral ledge 13 projecting horizontally from the opposite side thereof. The upper face of the ledge 13 is formed with an intermediate longitudinal rib 14 which together with the part 12, provides a recess 15 to receive the margin of a window pane. The upper surface 16 of the ledge 13 on the outer side of the rib 14 is preferably at a lower level than the recess 15. Cross bars 11 integral with the frame 10, divide it into sections to receive the glass. These cross bars as shown, have convex front faces, and their opposite or rear faces are formed with longitudinal spacing ribs 17.

The window glass as herein shown comprises hollow panes or blocks 18, each formed with an interior sealed space or chamber 19. The block is formed with front and rear marginal ribs 20 and 21 respectively, spaced apart to provide a recess 22. When the glass is placed in the frame, the rib 20 enters the recess 15. A lining or gasket 23 of asphalt or the like, is preferably attached, or applied to the frame in position to provide a backing for the glass and particularly for the flange portion 20. The bars 11 are also provided with a layer or facing 24 of such material.

The glass is secured in position in the frame by clamping devices comprising metal clips 25 positioned at intervals along the bars 11. These clips are preferably in the form of flat strips each having an end portion bent at right angles and inset into and flush with the face of the bar 11. The clips are spot-welded to the bars 11 and, as shown, are arranged in pairs with the clips on opposite sides of the ribs 17 and projecting outwardly beyond said ribs. When a pane of glass 18 has been placed on the frame, the free ends of the clips are bent to embrace the rib 20 of the glass and thereby securely hold the latter in place.

When panes of glass are placed in the frame, the adjacent edges of the glass provide longitudinal channels 26 which may be substantially rectangular in cross section. These are preferably packed with thermal insulating material 27, such as glass wool, rock wool, or other fibrous insulating material which may be introduced through the opening 28 provided between the ribs

21. The space 28 is then filled with caulking material 29 which may be any approved commercial caulking which is permanently sufficiently soft and elastic to maintain a tight seal. Caulking material 30 is also introduced between the frame 10 and the margins of the glass extending therewith along as indicated in Fig. 1. This caulking material extends inwardly and adjoins the lining 23. It will be seen that with this construction, the glass is separated from the metal frame by heat insulating and cushioning material. It will also be noted that the spacing ribs 17 are well insulated so that practically no heat can be transmitted through the space between the adjacent edges of the glass along said ribs.

Figs. 4, 5, and 6 illustrate a construction comprising a modified form of clamping device or fastening means for securing the glass in the frame. In this instance, screws 31 are provided at intervals along the bars 11 and are threaded into openings 32 in the bars, which openings may extend through the ribs 17. The glass is held in position by washers 33 clamped thereagainst by the screws. Gaskets 34 of comparatively soft resilient material are preferably interposed between the washers and the glass. The construction of the sash may be substantially the same as disclosed in Figs. 1 to 3, except for the use of a different form of clamping device.

Figs. 7 and 8 illustrate a modified form of sash, the outer frame of the sash in this instance is substantially of angle bar construction. The horizontal bottom member or base as shown, comprises a horizontal portion 35, a depending vertical flange portion 36 at the front edge of the part 35, and forming the face of the frame, and an intermediate upwardly projecting rib 37 which provides a backing for the plane of glass.

The vertical sides and the top rail of the frame may be of like construction. A layer 38 of asphalt or the like, is applied to the frame and provides a lining between the frame and the glass.

The sash as shown, comprises upright and horizontal cross bars 40 which are of a width to project beyond the opposite faces of the adjoining sheets of glass (Fig. 8). Each bar is formed with ribs 41 on opposite sides thereof to provide a backing for the glass. The crossbars are provided at intervals along their length with openings 42 therethrough to receive clamping devices in the form of metal holding clips 43. Each clip is formed from a strip or wire of resilient metal. The clip extends through the opening 42 and is spot-welded to the bar 40 and bent to the form shown. In this form it comprises a pair of forwardly extending divergent arms 44 with the end portions 45 thereof bent outwardly to engage the ribs 20 of the glass blocks or window panes when the latter are installed. When the glass is being placed in the frame, the resilient arms 44 spring inwardly allowing the glass to move into position and then spring outwardly behind the ribs 20 and hold the glass in position. The lining material 38 is then introduced to fill in the space between the adjoining edges of the glass. The clips 46 are substantially similar to the clips 43 except that they are formed with a single arm 44 and are attached at intervals along the frame 35.

It is sometimes desirable to divide the frame into smaller panels by means of intermediate cross bars 48 (Fig. 8). These cross bars are substantially H-shaped in cross section, being formed with flanges 49 to embrace the ribs 20. These cross bars 48 may be of comparatively light construction. The flange portions 49 of each bar 48

provide a backing for the glass in the same manner as the cross bars 11 (Fig. 6) while the intermediate portion of the bar 48 provides a spacing rib between the edge faces of the adjoining panes of glass by which the said edge faces are held spaced apart.

Modifications may be resorted to within the spirit and scope of my invention.

I claim:

1. A metal window sash comprising an outer frame having horizontal top and bottom frame members and vertical sides, and vertical and horizontal cross bars integral with said outer frame and dividing the frame into cells, said cross bars being formed with spacing ribs extending lengthwise thereof, said frame and cross bars having flat surfaces lying in the same plane and forming backing surfaces for panes of glass mounted in the sash and forming unbroken marginal surfaces in each cell extending along the sides and ends of the cell, and holding devices located at spaced intervals along the cross bars for holding said panes in place, said holding devices comprising pairs of sheet metal claps having end portions inset into and flush with said surfaces of the cross bars and welded to the cross bars with the clips of each pair positioned on opposite sides of a said rib and having their free ends projecting into position to be bent over the edges of the glass when the latter is placed in the sash.

2. A window including a sash comprising an outer frame and cross bars dividing the frame into compartments for individual plates of glass, the faces of said cross bars all lying in the same plane and forming a backing for the glass, said cross bars being formed with spacing ribs on said faces extending lengthwise of the bars, glass plates mounted in said frame with their adjacent edges spaced apart by said ribs, the thickness of said plates being greater than the depth of the ribs whereby longitudinal insulating spaces are provided between the adjacent edges of the said plates, and fibrous heat insulating material filling said insulating spaces and overlying said ribs, and clamping devices attached to the cross bars at intervals therealong and projecting outwardly between the said adjacent edges of the glass plates and gripping edge portions of the plates and thereby clamping the plates in position in the sash.

3. A window including a sash comprising an outer frame and cross bars dividing the frame into compartments for individual plates of glass, the faces of said cross bars all lying in the same plane and forming a backing for the glass, said cross bars being formed with spacing ribs on said faces extending lengthwise of the bars, glass plates mounted in said frame with their adjacent edges spaced apart by said ribs, the thickness of said plates being greater than the depth of the ribs whereby longitudinal insulating spaces are provided between the adjacent edges of the said plates, heat insulating material filling said insulating spaces and overlying said ribs, said edges of the plates being recessed and thereby increasing the cross sectional area of the insulating spaces, and clamping devices attached to the cross bars at intervals therealong and projecting outwardly between the said adjacent edges of the glass plates and overhanging and gripping edge portions of the plates and clamping the plates in position in the sash.

4. A window sash comprising an outer rectangular frame formed with a channel extending

therealong to receive the edges of the panes of glass, and cross bars dividing the frame into individual cells for the said panes, said cross bars each being formed with a spacing rib extending lengthwise thereof, said channels having flat inner surfaces forming a backing for the panes of glass, said cross bars having flat surfaces in the same plane with and merging into said channel surfaces, with the said surfaces forming in each cell an unbroken flat marginal surface extending along the sides and ends of the cell, and pairs of sheet metal clips positioned at intervals along said ribs with the clips of each pair arranged on opposite sides of the rib and bendable over the edges of the glass for holding the latter in position.

5. The combination of a window sash, window panes mounted therein with the inner major faces of said panes in the same plane, said panes having adjacent parallel faces narrowly spaced apart and formed with recesses extending lengthwise thereof and substantially rectangular in cross section thereby providing inner and outer ribs forming the side walls of said recesses, said sash comprising a cross bar positioned to provide a backing for said panes and having a spacing rib interposed between said parallel faces, said recesses together forming an insulating chamber, the outer surface of said spacing rib being substantially flush with the inner wall surface of the insulating chamber, and fibrous heat insulating material filling said chamber and overlying said spacing rib.

6. A window comprising a sash and window panes mounted therein with their front faces in the same plane and their rear faces in one plane, said panes having adjacent parallel edge surfaces between their major surfaces and each formed with a channel extending lengthwise thereof with the inner and outer walls of the channel forming inner and outer ribs rectangular in cross section, said frame comprising a cross bar extending along said adjacent edges of the panes and forming a backing for said panes, said cross bar having a longitudinal spacing rib positioned between the said inner ribs, said channels together forming an insulating chamber rectangular in cross section, and fibrous insulating material filling said chamber and overlying said spacing rib, the depth of said spacing rib being approximately equal to the thickness of said inner ribs, the said outer ribs being spaced apart to permit the introduction of said insulating material and having their opposite faces perpendicular to the adjoining wall surface of the said insulating chamber.

7. The combination of a window sash, window panes mounted therein with the inner major faces of said panes in the same plane, said panes having adjacent parallel faces narrowly spaced apart and formed with recesses extending lengthwise thereof and thereby providing inner and outer ribs forming the side walls of said recesses,

said sash comprising a cross bar positioned to provide a backing for said panes and having a spacing rib interposed between said parallel faces, said recesses together forming an insulating chamber, and insulating material filling said chamber and overlying said spacing rib, said spacing rib being provided with threaded openings located at spaced intervals along the cross bar, and holding devices comprising screws threaded into said openings and holding disks mounted on said screws and projecting laterally beyond the spacing rib into position to overlie the edges of the said panes, and adapted to clamp said panes in position in the sash.

8. A metal window sash made in a single piece comprising an outer rectangular frame and cross bars formed integrally therewith and dividing the frame into compartments, sheets of glass mounted in and individual to said compartments, said cross bars having glass supporting surfaces all lying in the same plane, said cross bars being formed with integral spacing ribs extending lengthwise thereof and projecting outwardly therefrom in position to provide abutments for the edges of the sheets of glass, said ribs extending lengthwise of the cross bars and each being positioned intermediate the longitudinal edges of the cross bar on which it is formed, whereby each said bar presents supporting surfaces for the margins of the sheets of glass on opposite sides of the spacing rib, said ribs being of substantially less depth than the thickness of the sheets of glass, fibrous heat insulating material overlying the said ribs and filling the space between the adjacent edges of glass, means for securing the insulating material in place, and clamping devices positioned at intervals along the cross bars and clamping the sheets of glass to said bars independently of the said insulating material.
